UNITED STATES PATENT OFFICE

JAMES L. KEMPTHORNE, OF MONTCLAIR, NEW JERSEY

ENGINE

Application filed April 1, 1931. Serial No. 526,813.

This invention relates to an engine adapted for use as a prime mover or as an engine for pumping or compressing purposes.

The engine is an improvement in the type 5 of engine illustrated and described in my application for Letters Patent filed November 25, 1930, Serial Number 497,780.

The object of the invention is to provide an engine in which the compressing member or 10 element which is rotary with an inclined face can be controlled without stopping the engine. This control enables the volume or capacity of the pump to be changed at will or automatically. This control adapts the engine to many various uses such as controlling 15 the speed of motors in vehicles propelled by a fluid drive. Other various uses can be found for an engine controlled as this one is by changing the position of the rotary member 20 in its inclination relative to the shaft with which it rotates.

The invention is illustrated in the accompanying drawing in which Figure 1 is a vertical longitudinal section of the engine, the 25 shaft and its associated parts being shown in elevation. Figure 2 is an end view of the rotary member and a ring in which it is journaled, the ring and the drive shaft being shown in elevation.

The engine illustrated comprises a casing 10 usually made in halves joined at the central part in line with the axis of the shaft and held together by bolts 11. The casing has inlet ports 12 and outlet ports 13 to which proper pipe connections can be made. The casing has a spherical opening 14 in which is a rotary member 15 having a face inclined to the axis of rotation of the shaft 16 with which it rotates. The outer part of the rotary member is a face plate 17 which does not rotate but gyrates or wobbles. The plate has a sealing strip 18 which fits into a recess across the centre of an abutment 19. The abutment is held against rotation but can oscillate horizontally under the influence of the changing angle of the face plate 17 of the rotary member. The abutment is mounted in an oscillatory member such as the ring 20 movable in a circular recess 21 in the side of the spherical opening and is secured thereto, as by

screws 22. The ring also serves to journal the sealing strip 18 which has its end 23 journaled in the ring 20. The abutment 19 has converging faces 24 with which the face of the plate 17 co-operates to compress first in 55 the upper chamber and then in the lower chamber as the rotary member 15 is rotated by the shaft.

It will be evident that if the face of the 60 face plate 17 was not at an angle to the axis of rotation it would have no compressing power. In other words, it would be at zero on pressure developed. As the angle increases the power or pressure increases 65 assuming no change in speed.

I have therefore devised a means for 70 changing the angle of the rotary member. The shaft has a laterally projecting shoe 25 secured to the shaft as by a screw 26. The shoe fits in a recess 27 in the rotary member 75 and thereby also acts as a key to insure the rotation of the parts in unison. The wall 28 of recess 27 can be directly engaged by the shoe but I prefer to interpose a roller or ball 29 to make the movement smoother. The roller 29 and a plate 30 against which it bears can be made of hardened steel as can also the shoe 25 and therefore have long life without the necessity of replacement. The pressure is 80 always delivered by the advanced half of the rotary member and this keeps the co-operating parts of the member and shaft in contact.

The shaft 16 is movable longitudinally and I show as a means for moving it, the lever 31, 85 pivoted at 32 and operating the collar 33 on the shaft. A pulley 34 is illustrated as means for driving the shaft.

When the shaft is pushed in the inclination 90 of the rotary member relative to the shaft is increased and the full capacity of the pump is exercised. When the shaft is drawn back the rotary member is allowed to straighten up and the angle of its face relative to the axis becomes less acute and the capacity of the pump is changed without necessitating any change in speed of the pump.

Various changes can be made in the proportions and shape of the parts without departing from the scope of the invention. 100

I claim:

1. An engine comprising a casing having a spherical opening therein, an abutment in one half the opening and having substantially flat faces converging toward the centre of the opening, a ring arranged at the circumference of the opening and to which the abutment is secured whereby the ring and abutment may oscillate together, a plate adapted to both rock and rotate, a sealing strip fitting between the centre line of the plate and the central line of the abutment, a rotary member in rear of the plate, a shaft for rotating the rotary member, and a connection between the shaft and the rotary member for varying the angle of the member relative to the shaft.

2. An engine comprising a casing having a spherical opening therein, an abutment in one half the opening and having substantially flat faces converging toward the centre of the opening, a ring arranged at the circumference of the opening and to which the abutment is secured whereby the ring

may oscillate together and rock and rotate to both rock and rotate so as to pop lock
